UNITED STATES PATENT OFFICE.

NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR A LABEL.

SPECIFICATION forming part of Design No. 29,755, dated December 6, 1898.

Application filed October 28, 1898. Serial No. 694,843. Term of patent 7 years.

To all whom it may concern:

Be it known that I, NICHOLAS WITSCH, a citizen of the United States, residing at Jersey City, in the county of Hudson and State 5 of New Jersey, have invented and produced a new and original Design for a Label, of which the following is a specification, reference being had to the accompanying drawing, forming a part thereof.

- 10 My design is intended for use as a label. In the accompanying drawing the design is shown on a rectangular panel. The design comprises a rectangular panel, in the center of which is shown, upon a clouded background, a crown in a diagonal position, through which is placed a burning cigar, forming an oblique angle with the crown. A

slight curl of smoke arises, and the ash of the burned portion is still retained in place. At either end of the design are placed three 20 medallions in a curving position, one above another. The border consists of short scrolls in imitation of carving, which inclose a section of lattice-work at the corners.

I claim—

25 The design for a label as herein shown and described.

In testimony whereof I, NICHOLAS WITSCH, affix my signature in presence of two witnesses.

NICHOLAS WITSCH.

Witnesses:

OTTO E. KUGLER,
GEO. SOMMER.
